UNITED STATES PATENT OFFICE.

JOHN FINNIE DOWNIE SMITH, OF ATLANTA, GEORGIA.

AEROPLANE.

Application filed April 15, 1925. Serial No. 23,310.

To all whom it may concern:

Be it known that I, JOHN FINNIE DOWNIE SMITH, a subject of the King of Great Britain, and a resident of Atlanta, in the 5 county of Fulton and State of Georgia, have invented certain new and useful Improvements in Aeroplanes, of which the following is a specification.

This invention relates to a device for controlling and propelling a vehicle and is more particularly directed to a device for operating an aeroplane.

An object of the invention is the provision of a device for causing elevating or lowering of an aeroplane and also for steering the plane and so cooperatively related that the elevating and steering devices may be combined for reversely driving the plane or for aiding in stopping the plane in a 20 short space.

A further object of the invention is the provision of a combination of devices for steering and elevating or lowering an aeroplane in the form of wings which may be brought together to form a pocket adjacent the propeller for forcing the aeroplane in a reverse direction.

This invention will be best understood from a consideration of the following detailed description, in view of the accompanying drawing forming a part of the specification; nevertheless it is to be understood that the invention is not confined to the disclosure, being susceptible of such changes and modifications which shall define no material departure from the salient features of the invention as expressed in the appended claims.

In the drawings:

40 Figure 1 is a side view in elevation of an aeroplane equipped with a combined steering and elevating device.

Figure 2 is a plan view of the same.

45 Figure 3 is an end view of the combined steering and elevating planes in closed position.

Figure 4 is a view in perspective of the cooperating elevating and steering planes in open position.

50 Figure 5 is a plan view of the structure shown in Figure 4.

Figure 6 is a side elevation of the same. Figure 7 is a top plan view of an aeroplane equipped with the propeller in rear of the lifting plane.

55

Figure 8 is a side elevation of the structure shown in Figure 7.

In aeroplanes generally a rudder is supplied at the tail of the aeroplane and the tail planes are usually equipped with elevators 60 which when operated will effect the riding or descent of the aeroplane. The elevators and rudder are operated through independent controls and are not coordinated in any manner, each performing its function independently of the other. In the present instance I have combined the elevators and the rudders in such a cooperative manner that they may form a closed pocket at some point adjacent or in line with the propeller 65 70 1 of the form of pusher plane 2. In this type of plane the propeller is located at the rear of the lifting planes 3 and tends to push the plane forwardly rather than pull it as in the case of the propeller located in 75 front of the planes; see Figures 7 and 8 for propeller in rear of plane.

According to the present construction I have provided a pair of horizontal shafts 4 and 5 at right angles to a pair of vertical 80 shafts 6 and 7. Rigidly mounted by means of sleeves 8 to the shaft 4 and rockable with said shaft is a triangular shaped elevator 9 curved along a definite arc as shown at 10. A second elevator is shown at 11 and is 85 similar in shape to the elevator 9. The lower elevator is rigidly connected by means of sleeves 12 to the shaft 5 and is rocked by said shaft towards or away from the elevator 9. A pair of rudders 13 and 14 are 90 rigidly connected to sleeves 15 to the respective sleeves 6 and 7 and are rocked simultaneously by the simultaneous rocking of said shafts. These shafts may be connected in any approved manner with a hand 95 lever located adjacent the driver's seat.

The upper edges 16 of the rudders 13 and 14 conform to the adjacent curved edges 10 of the elevators 9 while the lower edges 17 of said rudders conform to the curvature of 100 the curved sides 18 of the elevator 11. The rudders have their outer free ends sheared

off as shown at 19 to form straight sides, with the straight sides 19 adapted to be brought in close contact as shown at 20 in Figure 3. The elevator 9 is moved downwardly and has its free end as shown at 21 engaging the closed rudders at a point adjacent the rear of the contacting edges 19 and with the curved edges 10 in close contact with the upper curved edges 16 of the rudders 13 and 14. The curved edges 18 of the elevator 11 are brought into close contact with the lower curved edges 17 of the rudders 13 and 14 so that a closed pocket is provided in which the air which is forced rearwardly by the propeller 1 is engaged by this pocket and tends to force the pusher plane rearwardly.

It will be noted that the elevators 9 and 11 are shorter than the rudders 13 and 14 so that the ends of the elevators terminate short of the vertical edge 19 of the rudders.

It must be borne in mind that while I have shown the ends of the rudders 13 and 14 sheared off as at 19 the same may be formed substantially triangular in shape and to conform to the shape of the elevators 9 and 11 and in this case the outer ends 21 of the elevators will engage at a point where the free end of the rudders contact.

30 The rudders and elevators may operate in any approved manner for respectively guiding the plane or for causing elevating or lowering of the same by any approved means now in use. It must be further borne in mind that the combined rudders and elevators when brought to closed position form not only a pocket to cause the pusher plane to be driven in a reverse direction but will aid in bringing a plane to an early stop after the same lands upon a field and with such a construction the pocket will tend to cause a reverse direction and therefore bring a plane to such an early stop when lighting that the planes may make a landing upon the roof of a building.

It is evident from a consideration of Figure 6 of the drawing that only the elevator 11 is shorter than the rudders 13 and 14, the elevator 9 being of the same length.

50 In Figures 7 and 8 I show a pusher propeller plane without a tail and without a rear control, and while rear controls are shown in some figures of the drawing it is understood that in some instances they may not be necessary.

In the construction shown in Figures 7 and 8 it will be noted that the pusher propeller is located in a line between the lifting plane and the elevators and rudders thus getting practically a direct action of the propeller upon the elevators and rudders.

What I claim is:

65 1. In an aeroplane, a pair of elevators spaced from each other, a pair of rudders adjacent the elevators, said elevators and

rudders being adapted to be moved towards each other in such a manner as to form a pocket to receive air currents from the propeller and either retard the forward movement of the plane or for moving the plane 70 rearwardly.

2. In an aeroplane, a pair of vertical shafts spaced from each other, a pair of horizontal shafts spaced from each other, a rudder connected with each vertical shaft, 75 and an elevator connected with each horizontal shaft, and means for moving the elevators towards each other and means for moving the rudders towards each other in such a manner that the rudders and elevators will form a pocket to be effected by the air current from the propeller of the aeroplane to retard the forward movement of the aeroplane or for causing the aeroplane to be moved rearwardly. 80

3. In an aeroplane, a pair of vertical shafts spaced from each other, a pair of horizontal shafts spaced from each other, a rudder connected with each vertical shaft, 85 and an elevator connected with each horizontal shaft, and means for moving the elevators towards each other and means for moving the rudders towards each other in such a manner that the rudders and elevators will form a pocket to be effected by the air current from the propeller of the aeroplane to retard the forward movement of the aeroplane or for causing the aeroplane to be moved rearwardly. 90

4. In an aeroplane, a pair of vertical 105 shafts spaced from each other, a pair of horizontal shafts spaced from each other, a rudder connected with each vertical shaft, and an elevator connected with each horizontal shaft, the upper edges of the rudders being sheared off to form curved upper edges, said elevators being triangular in shape and curved downwardly, said elevators and rudders being adapted, when moved towards each other, to form a closed pocket 110 to receive air currents from the propeller of the plane. 115

5. In an aeroplane, a pair of vertical shafts spaced from each other, a pair of horizontal shafts spaced from each other, a rudder connected with each vertical shaft, 120 and an elevator connected with each horizontal shaft, the elevators being triangular in shape, the rudders having vertical edges where connected to the vertical shaft, the upper edges being curved downwardly with their outer ends being vertical, the triangular shaped elevators, when moved towards each other, and the rudders when moved towards each other, being adapted 125 130

to form a closed pocket with the side edges of the elevators engaging the upper curved edges and the lower horizontal edges of the rudders.

6. In an aeroplane, the combination with the lifting planes and elevators and rudders in rear thereof, of a propeller located between the lifting planes and the elevating

planes and rudders, said rudders and elevators being triangularly shaped and adapted to be moved towards each other to provide a closed pocket so that when the air is forced towards the pocket the forward movement of the plane will be retarded or the movement of the plane will be reversed.

J. F. DOWNIE SMITH.
